US0D1001055S

(12) **United States Design Patent** (10) **Patent No.:** **US D1,001,055 S**
(45) **Date of Patent:** **** Oct. 10, 2023**

(54) **CARRIER**

(71) Applicant: **Thule Sweden AB**, Hillerstorp (SE)

(72) Inventors: **Simon Helmersson**, Värnamo (SE);
Johan Larsson, Jönköping (SE)

(73) Assignee: **Thule Sweden AB**, Hillerstorp (SE)

(**) Term: **15 Years**

(21) Appl. No.: **29/825,494**

(22) Filed: **Feb. 2, 2022**

(51) **LOC (14) Cl.** **08-10**

(52) **U.S. Cl.**

USPC **D12/408**

(58) **Field of Classification Search**

USPC D12/115, 406–408, 412, 414

CPC B60R 9/10; B60R 9/08

See application file for complete search history.

(57) **CLAIM**

The ornamental design for a carrier, as shown and described.

DESCRIPTION

FIG. 1 is a top front isometric view of a carrier showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top front isometric view of another embodiment of a carrier showing the claimed design;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof; and,

FIG. 14 is a bottom plan view thereof.

The dashed broken lines in the figures show portions of the carrier that form no part of the claimed design.

The thick dot-dash broken lines in bottom plan views of the figures show boundaries that form no part of the claimed design.

The dash-dot broken lines and the portions between pairs of dash-dot broken lines that are broken away form no part of the claimed design.

1 Claim, 14 Drawing Sheets
